COAL GRATE

William D. Brunig, Norwich, N. Y.

Application July 26, 1956, Serial No. 42,398

Term of patent 14 years

(Cl. D81—18)

Fig. 1 is a perspective view of a coal grate showing my new design;

Fig. 2 is an end elevational view;

Fig. 3 is a top plan view; and

Fig. 4 is a front elevational view.

I claim:

The ornamental design for a coal grate, as shown.
